CASING PERFORATING GUN

James O. Tow, Huntington Park, Calif., assignor
to McCullough Tool Company, Los Angeles,
Calif., a corporation of Nevada

Application September 23, 1946, Serial No. 698,631

4 Claims. (Cl. 164—0.5)

1

My invention relates to guns employed for perforating casing in wells and relates in particular to that type of gun wherein the powder charge is fired by an ignition effect produced in or at the outer end of the gun barrel or between the outer end of the projectile and the outer end of the gun barrel, this ignition effect being produced by the explosion of an ignition charge of powder in a position ahead of the nose of the projectile so that the charge of powder in the chamber behind the projectile is fired either as the result of the driving of the projectile rearwardly to compress the firing charge or by flame or gases which pass rearwardly across the external face of the projectile into the firing charge.

It is an object of the invention to provide a perforating gun of simple construction having gun barrels removably supported in the gun body, these gun barrels being replaceable when wear or erosion makes this advisable.

It is a further object of the invention to provide a well perforating gun having a body with a laterally directed recess to receive a gun barrel which is of complex or composite form and comprises a number of parts arranged so that they may be separated when the gun barrel is removed from the recess, the separation of these parts opening or providing access to the powder chamber at the inner end of the gun bore.

A further object of the invention is to provide a well perforating gun of the character set forth in the preceding paragraph, wherein the cooperating parts of the gun barrel assembly are separable in a direction transverse to the axis of the gun bore, and a still further object of the invention is to provide a gun barrel having these characteristics wherein a main barrel member is provided with an axial bore to receive a projectile, a powder receiving space at the rear end of the bore, and a lateral opening leading from the powder receiving space which is closed by a wall member which is held in place by the side wall of the barrel-receiving recess when the barrel assembly is placed therein.

A further object of the invention is to provide a perforating gun having a body with a laterally directed recess with a forwardly faced wall or shoulder therein, a replaceable gun barrel insertable into this recess to a position to engage this wall or shoulder and a simple means for holding the barrel in the recess during use of the gun.

A further object of the invention is to provide a novel ignition unit for use in perforating guns.

Further objects and advantages of the invention will be brought out in the following part of the specification, wherein specific details of construction are for the purpose of fully disclosing

2

specific embodiments of the invention without limiting the scope thereof set forth in the appended claims.

Referring to the drawings which are for illustrative purposes only,

Fig. 1 is a partly sectioned elevational view of a portion of a perforating gun embodying my invention.

Fig. 2 is a cross section taken as indicated by the line 2—2 of Fig. 1.

Fig. 3 is a cross sectional view of a gun barrel wherein an alternative construction is shown.

Fig. 4 is a cross sectional view similar in general to Fig. 2, but showing a different gun barrel assembly.

Fig. 5 is a sectional view taken as indicated by the line 5—5 of Fig. 4.

In Fig. 1 I show a portion of a gun body 10 which consists of a cylindric bar of a size to be lowered into a well casing. Since the manner of supporting or suspending perforating gun bodies by means of cables or tubing strings is well known, I have merely shown that portion of a gun body embracing my invention. The gun body 10 has therein a plurality of laterally directed recesses 11 which preferably consist of cylindric bores formed on diametral lines and facing in different directions. Each of the recesses 11 has therein a forwardly faced wall or shoulder 12 to serve as stops against which the inner ends of inserted gun barrel assemblies 13 may rest. The recesses 11 have openings 14 at the rear ends thereof, through which force may be applied to the rear ends of the barrel assemblies 13 when it is desired to force them from the recesses 11.

As shown in Figs. 1 and 2, the gun barrel assemblies 13 are of cylindric form and fit relatively snugly in the recesses 11. Simple means in the form of screws 15 are provided for firmly securing the gun barrel assemblies 13 in the recesses 11. These screws 15 are operative in threaded openings 16, each of which communicates with a side of a recess 11 so that the inner ends of the screws 15 may engage the side walls or surfaces of the gun barrel assemblies 13, as shown. As best shown in Fig. 2, each gun barrel assembly 13 comprises a main barrel member 17 and a cooperating member 18.

The main barrel member 17 has therein an axial bore 19 to receive a projectile 20, and at the inner end of the bore 19 there is a chamber 21 to receive a powder charge 22. In the form of the invention shown in Fig. 2, the chamber 21 constitutes an enlargement at the inner end of the bore 19 formed by drilling an opening laterally in from a side of the member 17. At the outer end of the chamber 21 there is a counter-bore 23 having at its inner end a shoulder 24 against which the cooperating member 18 rests.

The powder chamber 21 is defined by the mem-

bers 17 and 18, and when these members 17 and 18 are moved apart, for example, by moving the cooperating member 18 laterally and outwardly with relation to the axis of the bore 19, when the barrel assembly 13 is removed from the recess 11, the chamber 21 will be open or accessible so that the powder charge 22 may be placed therein. In cooperation with the wall or closure 18 I provide a sealing member 25 comprising a plug which is pressed into the counterbore 23. When the member 18 and the plug 25 are in place, the wall 25' of the recess 11 prevents removal of the member 18, or, in other words, prevents separation or disassembly of the cooperating parts 17 and 18 of the barrel assembly 13.

In the outer end of each gun bore 19 there is a combined bore sealing and ignition unit 26. This unit 26 comprises a cylindric body 27 having a flange 28 at its outer end to engage the front end face of the member 17 when the unit 26 is pressed into the bore 19 thereof. Adjacent the flange 28, the body 27 has an annular channel 29 to receive a rubber sealing ring 30 which makes sealing engagement with the wall of the bore 19. At the inner end of the body 27 there is an inwardly faced cavity 31 in which an ignition charge 32 of powder is placed, after which the cavity is closed by an end wall or disc member 33. An electrical fuse or filament wire 34 extends within the chamber or cavity 31, and the ends of this wire 34 are carried outwardly through the member 27 to the exterior where they are connected to conductors 35 which lie in a spiral groove 36 disposed so as to intersect the outer ends of the recesses 11.

The firing of the gun shown in Figs. 1 and 2 is accomplished by directing electrical energy through the conductors 35, in a manner well known in the perforating gun art, so that the filaments 34 of the ignition units 26 will be heated so that the ignition charges 32 will be fired. The explosions of the ignition charges 32 will drive the projectiles rearwardly and the firing charges 22 will be exploded, propelling the projectiles 20 outwardly through the bores 19 at high velocity.

In the form of the invention shown in Figs. 1 and 2, the pressure of fluids encountered in the well are kept from forcing the projectiles 20 inwardly by the sealing and ignition units 26 having flanges 28 so that they cannot be forced inwardly from the positions in which they are installed in the gun bores 19. In Fig. 3 I show a gun barrel assembly 13a which is mostly comprised of the same parts as the barrel assembly 13 shown in Fig. 2. Therefore, these corresponding or identical parts will be identified by the numerals previously used so as to avoid repetition of description. In Fig. 3 I show a sealing and ignition unit 26a which is inserted in the bore 19 and has its end wall 33' recessed so that it will fit over the nose of the projectile 20. This unit 26a differs from the unit 26 shown in Fig. 2 in an additional respect—namely, that it does not employ a flange 28, but has a rubber sealing plug 38a at its outer end for sealing the bore 19 against entry of fluid. At the inner end of the projectile 20 there is means 38 for preventing inward movement of the projectile 20 from the position in which the projectile is shown by the hydraulic pressure of the well exerted against the sealing plug 38a. The means 38 is shown as a perforated metal disc disposed in the firing charge chamber 31. It may be made frangible so that the explosion of the ignition charge 32a

will cause it to be crushed by the inwardly driven projectile 20, or this means 38 may be of such strength that it will prevent inward movement of the projectile 20 under the force of the explosion of the ignition charge 32a. In this latter event, the firing charge 22, Fig. 3, will be ignited by the flame and products of combustion from the explosion of the ignition charge 32a which pass through the rearward portion of the bore 19, across the outer face of the projectile 20 into the powder chamber 31, it being understood that a small space existing between the surface of the projectile and the wall of the bore 19, forms a passage for the combustion products.

In Figs. 4 and 5 I show a gun body 16a having a recess 11a of cylindric form with a shoulder 12a near its front end instead of near the rear end of the recess as shown in Figs. 1 and 2. A gun barrel assembly 40 is provided having at its front end flange means 41 for engagement with the shoulder 12a. This barrel assembly 40 has a bore 42 to receive a projectile 43, and a powder chamber 44 is provided at the rear end of the bore 42 to receive a firing charge 45.

The barrel assembly 40 of Fig. 4 comprises separable parts for accomplishing access to the powder chamber 44 when the assembly 40 is removed from the recess 11a. These separable parts include a pair of symmetrical, semi-cylindrical body members 46 so as to provide an outer shell 47 for the assembly 40 which is divided along a median plane 48.

Leading inwardly from its front end, the shell 47 has an axial opening 50 to receive a steel tube 51 in which the bore 42 is formed and which has at its rear end a rearwardly faced cavity 52 which cooperates with a plug or closure 53 in forming the powder chamber 44. The closure 53 is provided with a sealing ring 54. In the outer end of the projectile receiving bore 42 there is a sealing and ignition unit 55 which combines the characteristics of the units 26 and 26a shown in Figs. 2 and 3. That is to say, this unit 55 has an external flange 28' which rests against the outer end of the tubular member 51, has a sealing ring 39' adjacent the flange 28' and has at its inner end a recess wall 33a which fits over the nose of the projectile 43. The unit 55 carries an ignition charge 32b arranged to be exploded by the heating of a filament 34a so as to produce a force which will drive the projectile 43 rearwardly to cause the firing of the powder charge 45.

I claim as my invention:

1. In a well perforating gun, the combination of: a gun body having a laterally directed gun barrel recess; a gun barrel assembly insertable into said recess, said gun barrel assembly comprising a main barrel member having a bore for receiving a projectile, a powder receiving space at the inner end of said bore, said space having an opening leading out through the side of said main barrel member, and a wall member to close said opening, said wall member being arranged so that it will be held in place by the side wall of said recess when said barrel assembly is in said recess; yieldable means for placement in said powder receiving space for resisting inward movement of said projectile; and means in the outer end of said bore to produce an explosion which will drive said projectile into said powder receiving space.

2. In a well perforating gun, the combination of: a gun body having a laterally directed gun barrel recess; a gun barrel assembly insertable

into said recess, said gun barrel assembly comprising a main barrel member having a bore for receiving a projectile, a powder receiving space at the inner end of said bore, said space having an opening leading out through the side of said main barrel member, and a wall member to close said opening, said wall member being arranged so that it will be held in place by the side wall of said recess when said barrel assembly is in said recess; means for resisting inward movement of said projectile; and means in the outer end of said bore to produce an ignition effect in the outer part of said bore which will pass by the projectile and ignite the powder charge in said powder receiving space.

3. In a well perforating gun, the combination of: a gun body having a bore for receiving a projectile, and a powder receiving space at the inner end of said bore; a projectile in said bore; a charge of powder in said space; yieldable means distinguished from said powder disposed in said powder receiving space so as to engage and resist inward movement of said projectile and thereby prevent compression of powder in said chamber as the result of inadvertent inward movement of said projectile; and means in the outer end of said bore to produce an explosion which will drive said projectile into said powder receiving space.

25

4. In a well perforating gun, the combination of: a gun body having a bore for receiving a projectile, and a powder receiving space at the inner end of said bore, said space having a rear wall; a projectile in said bore; a charge of powder in said space; means distinguished from said powder disposed in said powder receiving space in a position passing through said space from said rear wall to the rear end of said projectile so as to resist inward movement of said projectile; and means in the outer end of said bore to produce an ignition effect in the outer part of said bore which will pass by the projectile and ignite the powder charge in said powder receiving space.
